UNITED STATES PATENT OFFICE.

BENJAMIN E. GETCHELL, OF PLAINVILLE, CONNECTICUT, ASSIGNOR TO THE TRUMBULL ELECTRIC MANUFACTURING COMPANY, OF PLAINVILLE, CONNECTICUT, A CORPORATION OF CONNECTICUT.

SPRING MEANS FOR ELECTRIC SWITCHES.

Application filed March 10, 1923. Serial No. 624,141.

My invention relates particularly to operating springs used in enclosed switches, and has for its main object the provision of practical means for adjusting the tension of the spring. I have also sought to provide means which can be readily installed at a minimum of expense.

The invention is particularly adapted to quick-break switches and what are sometimes termed "automatic circuit breakers" in which it is important to have the tension of the spring properly adjusted to the load at which the switch is intended to operate.

Figure 1 is a perspective view of a switch embodying the improvements of my invention, the switch box being shown open.

Fig. 2 is a longitudinal sectional view with the cover closed and the switch in the closed circuit position.

Fig. 3 is a perspective view of parts of the adjusting device.

Fig. 4 is a fragmentary side view of the adjustable connection, partly in section.

The box or receptacle in the form shown has a body 5 and a cover 6 of any suitable construction.

The switch proper has one or more blades 7 and an operating crank 8 connected to the switch blade or blades, for instance by means of brackets 9, or in any other suitable manner. An operating handle 10 is provided exterior to the box and connected to the operating crank 8.

In the particular form shown the switch is provided with an electro-magnet having a coil 11 and an armature 12 which is hinged at 13. A link 14 is connected at one end to the crank 8 and has a sliding engagement 15 with the armature 12. One end of the link normally abuts against a roller 16 carried by the armature when the parts are in the closed circuit position with normal current on.

The spring 17 is anchored at one end to a wall of the box by means of a screw 18 and a co-acting member 19. The spring is a coiled spring of usual form and the member 19 has an integral flange 23 shaped to conform to the coils, and adapted to be screwed into the end coils of the spring. The central portion of the flange 23 is drawn to a diameter approximately equal to that of the coils of the spring to provide a retaining shoulder 24 for centering the mem-

ber 19 relative to the spring. The end of shoulder 24 is further drawn and interiorly threaded as at 20 to receive the end of an adjusting screw 18. A check nut 21 is also preferably provided. The opposite end of the spring 17 may be hooked over a ring 60 or bushing 22 on the crank 8. This construction provides two methods of adjustment for the tension on the spring. For small changes in tension the screw 18 is turned in the threads 20, while for greater adjustment the whole member 19 is screwed into or out of the spring.

From this it will be seen that when the switch is in the closed circuit position of Fig. 2 the spring 17 is pulling upon the crank 8 thus tending to throw the switch into open circuit position. If the current is on and of normal voltage, the magnet coil 11 will hold down the armature 12 in opposition to the thrust of the link or bar 14 against the roller 16. If the circuit through the coil 11 is opened at some exterior point, or if the field becomes weakened below a pre-designed value the armature will be released and the pull of the spring will be sufficient to tilt the armature so as to release the link 14 and thus allow the crank 8 to be moved by the spring and the switch 7 to be opened. It is important therefore that the tension of the spring be properly adjusted to the conditions under which the switch is to operate. By my construction it will be seen that it is simply necessary to loosen the check nut 21 and turn the screw 18 which is accessible at the outside of the box. The member 19 may be readily screwed into the end coils of the spring 17 and it will be held there securely by the normal tension of the adjacent coils and lateral shifting of the member will be prevented by the shoulder 24 which fits within the end coils of the spring.

In practice the springs are usually tight-wound but when in use, the coils open up according to the tension placed upon the spring.

It is obvious however that all of the coils of the spring which have been threaded past the member 19 will remain undisturbed regardless of how much the coils on the other side of the member may have spread or opened, which fact greatly assists in retaining the member 19 in fixed engagement with

the spring. In the manufacture of the parts at the factory the member 19 is first screwed into the end of the spring 17 to a position which is approximately correct for 5 the particular type of switch in which it is intended to be used. When the parts are assembled in the box the screw 18 is inserted through a wall of the box, the nut 21 screwed part way on to the screw and the end of 10 the screw inserted into the member 19. The screw 18 is then adjusted accurately so as to provide exactly the right tension for that particular switch. The check nut 21 is then tightened so as to hold the screw in fixed 15 position. Obviously the parts may be operated in the reverse order so that to disengage or dismount the spring 17 it is simply necessary to loosen the nut 21 and withdraw the screw 18.

20 While this means for adjusting the switch throwing spring is particularly useful in switches of the magnetically controlled type, it is obvious that the invention may be ap-

plied to any form of switch having a throwing spring of the coiled type or in fact to 25 any construction in which it may be desirable to adjust the tension of a coiled spring.

I claim:

An electric switch construction comprising a box, a switch member within said box, 30 a coiled operating spring connected at one end to said switch member, an anchor member having a flange portion engaged in the coils at the other end of said spring, said anchor member having a threaded neck, an externally operable adjusting screw passing through one wall of said box and into adjustable engagement in the threaded neck of 35 said anchor member and having a head outside of said box and a lock nut for said adjusting screw inside of said box, the flange of said anchor member being rotatably adjustable in the coils of said spring without rotating said spring.

BENJAMIN E. GETCHELL.
